UNITED STATES PATENT OFFICE.

JOHN E. McCARTHY, OF CINCINNATI, OHIO, ASSIGNOR TO THE AMERICAN LAUNDRY MACHINERY COMPANY, OF CINCINNATI, OHIO, A CORPORATION OF OHIO.

DAMPER FOR BLANKET AND CURTAIN DRYING MACHINES.

Application filed September 28, 1927. Serial No. 222,675.

This invention relates to drying apparatus and more particularly to that class of blanket and curtain drying apparatus in which stretcher frames are arranged for movement into and out of a drying room through openings therein, each stretcher frame having end members adapted to close its opening portion when the frame is in outer and inner positions respectively; the purpose of such closure arrangement being to prevent loss of heat and protect the contents of the drying room, as, for example, articles on other stretcher frames therein, from exposure to cold air. Ordinarily a means for passing heated air through the room is provided and such means conveniently has a warm air entrance in the ceiling of the room and an egress opening along the lower portion of the rear wall thereof; the tops of the frames being substantially open and perforations being provided in the rearward end walls thereof to allow passage of the air to the exit opening of the room.

Specifically, the object of my invention is to provide improved means for controlling these perforations whereby they are covered except when the frame is in inner position in the drying room. The exact nature, further objects and advantages will be apparent from the following description taken in connection with the accompanying drawings in which Fig. 1 is a longitudinal sectional elevation of drying apparatus in which my invention is incorporated, the stretcher frame being shown in inner position in the drying room; Fig. 2 is an end elevation of the lower portion of the rear end member of the drying frame showing details of the damper thereon arranged according to my invention; Fig. 3 is a side elevation of the parts appearing in Fig. 2; and Fig. 4 is a view similar to Fig. 3 but showing the perforations in the end member closed by the damper.

In the drawings, the drying room is arranged upon the floor 1, having side walls 3, rear end wall 2, and ceiling 4, the forward end of the drying room being open. Extending along the floor through the opening are tracks 5 upon which the stretcher frames 6 mounted on the rolls 7 are arranged for movement into and out of the drying room. Details of the stretcher frames are immaterial here except that the forward members 8 thereof are arranged to close the

opening of the drying room when the frames are in the position indicated and the rearward walls 9 are similarly arranged to close the opening when the frames are moved on their tracks to outer position, the end wall 9 of each frame closing its respective portion of the opening. Rearward of the drying room is a motor 10 arranged to drive a blower 11 to draw air past the heating coils 12 through the volute 13 of the blower, passage 14 and into the drying room through the ceiling 4 thereof. Rearward of the drying room is a passageway 15 through which exhaust from the room may be had, whereby a circulation of warm air over the contents 16 of the stretcher frames in the room may be maintained by the blower.

Since in order to properly close the forward opening in the room when the several stretcher frames are withdrawn therefrom, it is necessary that the end members of the frames extend substantially the full width of each frame portion of the room, some means is necessary for passing the circulating air through the rear walls 9 of the frames, and it is convenient for this purpose to perforate the rear end walls as at 16. When these perforations are provided, however, it becomes necessary that means for closing them be also provided, that the room opening be sealed when the frames are withdrawn. For this purpose a damper 17 is conveniently mounted on the rear end wall of each stretcher frame, the damper having perforations 18 corresponding with the perforations 16 and being arranged for vertical sliding movement as by the slots 19 underlying studs 20 secured with the end walls 9. By such arrangement when the damper 17 is in lowered position, determined by the stop 21, the perforations 16 are closed, but may be opened by raising the damper 17.

For controlling the movement of the damper, I provide thereon a roller 21 carried by a bracket 22 and adjustable on the damper as by a set screw 23, a bolt 24 being provided to secure the bracket 22 with its roller 21 in adjusted position, the set screw 23 being mounted in a bracket 25 secured with the damper 17 as by bolts 26. On the floor 1 adjacent the rear wall 2 of the drying room and aligned with the roller 21, is a bracket 27 having a cam finger 28. The rise of the cam on the finger 28 is such that when the roller 21 is properly adjusted, the damper 17

17 will be raised to uncover the apertures 16 of the frame end wall, and the bracket 27 is positioned so that such damper movement will be effected as the frame is moved to extreme inner position, a flat 29 being provided on the extremity of the finger 28 whereby tendency to move the frame outwards is avoided.

The operation of the arrangement described will be apparent, the damper 17 being allowed to lower under its own weight immediately as the frame moves forward from the drying room position.

What I claim is:

- 16 1. Drying apparatus, comprising a drying room, a stretcher frame movable into and out of said room through an opening therein and having a member adapted to close said opening when moved to outer position, said member being perforated; a damper movable on said member to open or close said perforation, and cam means arranged to control said damper movement dependent upon said movement of said frame.
- 20 2. Drying apparatus, comprising a drying room having an opening, a stretcher frame arranged for movement into and out of said room through said opening and having a perforated member adapted to close said opening when said frame is in outer position, a damper arranged for sliding movement on said member to control said perforation, and cam means arranged to move said damper to close said perforation when said frame is moved to said outer position.
- 25 3. Drying apparatus, comprising a drying

room having an opening; a stretcher frame arranged for movement into and out of said room through said opening and having a perforated wall adapted to close said opening in outer position, a damper mounted for sliding movement on said member to control said perforation, and cam means for moving said damper to uncover said perforations when said frame is moved to inner position.

4. Drying apparatus, comprising a drying room having an opening, a stretcher frame arranged for movement into and out of said room through said opening and having a perforated wall adapted to close said opening in outer position, a damper mounted for raising and lowering movement on said wall to uncover or cover, respectively, said perforations, and cam means for raising said damper to uncover said perforations as said frame is moved to inner position.

5. Drying apparatus, comprising a drying room having an opening, a stretcher frame arranged for movement into and out of said room through said opening and having a perforated member adapted to close said opening in outward position, a damper arranged for raising and lowering movement on said wall to uncover and cover, respectively, said perforations, and a cam arranged in said room to elevate said damper to uncover said openings as said frame is moved to inner position.

In testimony whereof I hereby affix my signature.

JOHN E. McCARTHY.
